UNITED STATES PATENT OFFICE.

WILLIAM STRONG, OF INDIANAPOLIS, INDIANA, ASSIGNOR OF ONE-HALF
TO CHARLES ANESHAENSEL, JR., OF SAME PLACE.

SHOWER ATTACHMENT FOR BATH-TUBS.

SPECIFICATION forming part of Letters Patent No. 341,183, dated May 4, 1886.

Application filed August 10, 1885. Serial No. 173,973. (No model.)

To all whom it may concern:

Be it known that I, WILLIAM STRONG, a citizen of the United States, residing at Indianapolis, in the county of Marion and State 5 of Indiana, have invented certain new and useful Improvements in Shower Attachments for Bath-Tubs, of which the following is a specification.

Heretofore the shower device connected with 10 bath-tubs was either stationary—a pipe running from the bath-tub supply up on the wall of the room or on a board fixed for that purpose, and at a certain height branching over the bath-tub ending in a downward shower— 15 or it consisted of a detachable flexible hose, terminating in a sprinkler or shower, which hose had to be connected with the bath-bib whenever the shower was to be used and disconnected when supply was needed in the 20 bath-tub. The objections to the former kind of a shower device were as follows: Cocks for hot and cold water had to be provided in the supply-pipes to the shower, thus creating considerable expense. If these cocks were not 25 always closed tightly after using the shower, or if the same became leaking in the least degree, the drippings from the shower discolored and injured the bath-tub, making it nearly impossible to keep the same clean and bright. 30 To the detachable hose and shower device the following objections were found to exist: The handling of the hose and its heavy shower-casting more or less injured the bath-tub lining and the surrounding wood-work. If by 35 carelessness the shower were allowed to drop into the tub, the same became disfigured, and in some instances leaking. Further, the shower not being stationary right over the bath-tub, careless persons, especially in public bath- 40 houses, in handling the shower wetted and injured the surrounding furniture and wood-work. I overcome all these objections by the device illustrated in the accompanying drawing, which shows the end of a bath-tub and 45 its supply-cocks, the shower, and the shower-connection.

A is the bath-tub; C, the common combination bath-bib and cocks for hot and cold water.

50 B is a stationary vertical pipe starting from

above the top of the bath-tub and running up on the wall W or on a board and projecting out horizontally at a suitable height over the bath-tub, ending in a downward shower or sprinkler, b. The pipe B is provided at its 55 lower end with a screw-thread or a coupling, to which is screwed one end of a rubber or flexible hose, R. The other end of this hose R must be attached, when the shower is to be used, to the bath-bib C, and is hung up or supported, when not thus connected, by a hook or bracket, H, located at a convenient place near the pipe B.

By using the stationary pipe and shower B b the liability of wetting the surroundings and 55 of injuring the lining and wood-work of the bath-tub, which invariably follows the use of a detachable rubber hose and shower, is avoided; and by using a detachable rubber hose-connection between the bottom end of the fixed 70 shower-pipe B and the bath-bib cock C, I am enabled to turn the supply into the shower without the use of separate shower-cocks, as necessary in the shower devices now in use with stationary pipe and sprinkler, and I avoid the 75 inconveniences caused by the leaking of such cocks. Thus my shower attachment possesses the advantages of both the stationary and the detachable shower device, and overcomes the 80 objections raised to either of them.

Having thus fully described my improvements, what I claim, and desire to secure by Letters Patent, is—

The combination, with the wall, of the metal pipe B, attached vertically thereto and bent 85 inwardly at its upper and lower ends and extending from a point just above the tub to the desired height, a shower attachment on the inner upper end of the pipe, and a short flexible tube connected with the lower end of said 90 pipe and adapted to be connected with the bib or faucet C, as set forth.

In testimony whereof I have signed my name to this specification in the presence of two subscribing witnesses.

WILLIAM STRONG.
